UNITED STATES PATENT OFFICE.

WILLIAM NEVINS COOK, OF NEW YORK, N. Y., ASSIGNOR TO E. B. MEYROWITZ, INC., A CORPORATION OF NEW YORK.

GOOGLE.

Application filed November 5, 1926. Serial No. 146,315.

My invention relates to goggles and particularly to the construction of the cushions which are necessary as a part of the goggles, for providing a seal and padding between 5 the goggle frame and the wearer's face.

Goggles are an essential part of the equipment of all those who are engaged in high speed transportation. My invention provides goggles of a particularly advantageous 10 type of construction for the use of aviators, automobilists, etc. for providing the necessary protection against dust and flying small objects, as well as against the wind stream caused by rapid motion.

15 Goggles of various types have customarily been part of aviators' and automobilists' equipment in the past, but the advent of extremely high speeds of transportation such as those provided by the newer patterns of 20 aeroplanes, traveling at speeds much in excess of 150 miles an hour, has shown the previous models of goggles to be inadequate, in that they do not properly seal the space behind the eye-lens from the wind stream, 25 nor do they under all conditions protect the wearer from injury, but may themselves be a source of injury.

My invention provides a goggle construction embodying a sponge rubber cushion 30 having a channeled holding means, which is adapted to provide means for firm attachment of the cushion to the goggle frame, by an attachment which is readily removable for change, and to protect the wearer's face 35 against contact with the goggle frame when a sidewise pressure is exerted upon the goggle.

In my co-pending application, Serial No. 747,168, is disclosed a goggle construction 40 having a lens, a lens frame, a nose-piece, and a sponge rubber cushion. The cushion, as disclosed, has different thicknesses and different cross sectional areas at different portions of its circumference. It has likewise 45 an integral sewing lip by which it may be attached to the frame of the goggle by a removable stitching. The cushion, as disclosed in the co-pending application, is thus adapted to be adjusted in its position to 50 bring the point of maximum cross section into the deeper hollows on the wearer's face and thereby provide a much better seal against air currents than is made by any other structures of the prior art. The construction, disclosed in the co-pending appli-

cation, is entirely satisfactory for general automobile service and for most aeroplane service. However, at the extremely high speeds obtained by aeroplanes recently designed, speeds ranging above 150 miles an 60 hour for instance, some difficulty has been experienced with the construction there disclosed. It is found that if the aviator turns his head sidewise, a strong pressure is exerted on the goggle which tends to displace it 65 sidewise. This pressure at the very high speeds may be sufficient to produce a rolling effect of the cushion and may displace it 70 sidewise from under the edge of the goggle frame. Upon return of the aviator's head to 75 the forwardly facing position, and the resumption of pressure in the original, normal, direction from the wind stream, it sometimes happens that the goggle frame does not 80 promptly return to its original position over 85 the cushion but remains displaced sidewise. The wind pressure may then be sufficient to drive the goggle frame downward beside the cushion and bring the edge of the frame into contact with the wearer's skin, with the 90 cushion displaced to one side and therefore furnishing insufficient protection, even though it still makes a tight seal against the admission of air underneath the goggle.

My invention provides means for avoiding this difficulty. I provide a cushion having a channel portion integral therewith, which is adapted to hold the cushion to the goggle frame. This may be used to provide a wedging effect somewhat similar to the 95 principle involved in clincher tires, or it may, by being made in slightly different form, be used in a manner similar to that of the cushion in the co-pending application, and sewed to the goggle frame.

Other objects and structural details of my invention will be apparent from the following description when read in connection with the accompanying drawing, wherein:

Fig. 1 is an inside elevation of a pair of 100 goggles, having attached thereto cushions constructed in accordance with my invention;

Fig. 2 is a plan view of the same embodiment showing also a sectional view of one of 105 the cushions, goggle frame and lens;

Fig. 3 is a view of the same embodiment of the cushion of my invention showing the double lip construction; and

Fig. 4 is an enlarged sectional view of the 110

same embodiment showing further details of the double lip, stitching, and goggle frame.

Referring to the figures, I provide goggle frames 1, having lenses 2, a connecting bridge-piece 3 and a head strap 4. The lens elements 2 may desirably be of clear glass or may be chosen of tinted glass, or such other modifications may be made as are found desirable. The connecting bridge-piece 3 may desirably be made adjustable to accommodate the different pupillary distances of different wearers.

Cushions 5 are provided and attached to the frame 1. The cushions 5 may be formed of sponge rubber in ring shape, as shown in Fig. 3, and may be of different sectional area at different points in the circumference as indicated. The cushions are provided with two sewing lips 6 and 7, as shown in detail in Figs. 2, 3 and 4, which are adapted to be positioned on either side of, and surrounding the sewing edge of the frame 1.

In the assembling of the goggle, the various elements may be put together at the factory with the exception of the cushions. The proper position of the cushions may then be determined by the wearer to whom they are supplied, and they may then be attached in that position to the goggle frame by means of the stitching 8. This may desirably be a stout thread and may be inserted by the wearer, himself, or under his direction, by means of a usual needle. Care is to be taken that the edge of the goggle frame fits well down to the bottom of the groove between the sewing lip 6 and 7 in order that the maximum width of margin may be obtained between the perforations through which the thread passes and the edge of the cushion sewing lip.

In the preceding description, I have disclosed a cushion construction having double lips which are adapted to be sewed to the frame of the goggles, in order to hold the cushion in place. I have found that when the cushions are attached in this way, that they are firmly and satisfactorily held. It is, however, not necessary that the cushion be held in place by a stitching through the respective lips and the frame, but they may be held in place by other convenient means. For instance, it is readily possible to provide a thicker lip, formed in a shape which is adapted to interlock with a stamped crevice in the frame, so that the cushions are held in place without the necessity of stitching. Likewise it is readily possible to make the lip slightly longer and hold it in place by clamping means on the inside and outside of the goggle frame. Alternatively it may be convenient to form the lip of a semi-hard rubber, which may be adapted to button over a series of small rivets, or may be held in place by other convenient locking means. Likewise it may be preferred to mold the

cushion with inserts of a harder material which may be adapted to interlock with the frame member of the goggles.

By these constructions, it will be seen that no matter how much the goggle frame is 70 displaced sidewise, and the cushion rolled from under the edge, it will not be possible for the material forming the sharp edge of the goggle frame to be bared so that it can make direct contact with the wearer's skin 75 with the possibility of cutting the skin because of the pressure produced by the wind.

By these constructions of my invention, I produce a goggle, having a cushion which provides exceptional softness of padding between the goggle frame and the wearer's face, which provides exceptional tightness of fit and seal against air currents and flying objects, and which provides protection against the possibility of injury of the 85 wearer's face by the edge of the frame when the goggle is displaced sidewise by wind pressure.

While I have shown but two embodiments of my invention in the accompanying description, it is capable of various modifications therefrom without departing from the spirit thereof, and it is desired therefore that only such limitations shall be imposed thereon as are required by the prior art or 95 indicated in the appended claims.

I claim as my invention:

1. A goggle comprising a lens frame, an annular cushion, the radial cross-section of which is a closed figure free from reentrant portions and forming a body, a pair of relatively thin, flexible extensions projecting from one face thereof, said extensions being substantially parallel and continuous, and means for securing said extensions to 100 the lens frame with the body in the rear thereof.

2. A goggle cushion formed as an annulus, the radial cross-section of which varies in area at different points and is a closed figure of curved outline forming a body with a pair of relatively thin, flexible extensions projecting therefrom and providing means for securing said cushion to the lens frame with the body in the rear thereof. 110

3. A goggle comprising a lens frame, an annular cushion having substantially parallel and relatively thin and flexible outer and inner extensions projecting from one face thereof, and means for securing said extensions to the lens frame with the body in the rear thereof, one of said extensions being interior to said frame to resist displacement of the cushion in an outward direction and the other extension being exterior to the 120 frame to resist displacement of the cushion in an inward direction.

4. A goggle cushion formed as an annulus, the radial cross-section of which is a closed figure free from reentrant portions and 130

forming a body, a pair of relatively thin, flexible extensions projecting from one face thereof and constituting substantially parallel and continuous means for attachment of said cushion to a goggle lens frame with the entire body except said extensions positioned in the rear thereof.

5. A goggle cushion formed as an annulus having a pair of relatively thin and flexible extensions projecting from one face thereof,

said extensions being substantially parallel and continuous and adapted to engage and be attached to opposite sides of a goggle lens frame with the entire cushion, except said extensions, positioned in the rear of the goggle lens frame.

10. In witness whereof, I hereunto subscribe my signature.

WILLIAM NEVINS COOK.
